ATTORNEY

UNITED STATES PATENT OFFICE

FREDERICK SCHWEIGERT, OF NEW YORK, N. Y.

WRENCH

Application filed May 6, 1929. Serial No. 360,703.

This invention relates to new and useful improvements in wrenches.

The invention has for an object the provision of a device of the class mentioned which is of simple durable construction, dependable in use and efficient in action, and which may be manufactured and sold at a reasonable cost.

The invention proposes the use of detachable biting pieces for the jaws of wrenches, arranged to be quickly and firmly adjusted and held in place upon the jaws so as to be exchangeable on the jaws of various wrenches, which is of extreme advantage in that new attachments may be engaged on wrenches to take the place of worn and damaged ones.

For further comprehension of the invention, and of the objects and advantages thereof, reference will be had to the following description and accompanying drawings, and to the appended claims in which the various novel features of the invention are more particularly set forth.

25 In the accompanying drawing forming a material part of this disclosure:—

Figs. 1, 3 and 4 are side elevational views of wrenches of different designs constructed according to this invention.

30 Fig. 2 is a vertical sectional view taken on the line 2—2 of Fig. 1.

Fig. 5 is a vertical sectional view taken on the line 5—5 of Fig. 1.

Fig. 6 is a vertical sectional view taken on the line 6—6 of Fig. 1.

Fig. 7 is an enlarged view of a modified form of invention.

The reference numeral 10 indicates generally the stationary jaw of a wrench, said jaw being connected with a handle 11 and is formed with a central opening 12. A movable jaw 13 with an integral lead thread 14 slidably engages in the stationary jaw and passes thru the opening 12. A control nut 15 is rotatively mounted in the opening 12 and threadedly engaged upon the lead thread 14 for adjusting the position of the movable jaw. A biting piece 16 is attached upon the movable jaw by rivets 17 and by 50 a dovetail connection 18. The stationary

jaw 10 has upper and lower working faces, and a V-shaped biting piece 18' is mounted upon the stationary jaw and held in fixed positions by rivets 19. This V-shaped biting piece has tongue elements 20 engaging in grooves formed in the stationary jaw. The nut 15 may be rotated until the movable jaw is completely disengaged therefrom and then this movable jaw may be inserted thru the nut from the opposite side so that the movable jaw now coacts with the lower operating face of the stationary jaw.

In the modified form of the device illustrated in Fig. 3, a stationary jaw 10^a has been illustrated provided with four working faces indicated by reference numerals 21. Each of these working faces are provided with biting pieces 22 held in fixed positions by rivets 23. This wrench is also provided with a movable jaw 13 and a control nut 15. The operation of this wrench is similar to the one previously described but differs in that the movable jaw may be turned for co-acting with any of the four working faces of the stationary jaw. The lead thread 14 is provided with grooves 24 engageable by projections from the stationary jaw to hold the movable jaw against rotation while the control nut is being rotated. The wrench shown in Fig. 1 is also provided with grooves 24 for the same purpose.

The wrench illustrated in Fig. 4 is similar in construction to that shown in Fig. 1 but differs in that the handle 11^b is disposed at an inclination to the stationary jaw. Another point of difference between this wrench and the one shown in Fig. 1 is that the biting piece 18^b upon the stationary jaw is formed of two separate sections independently secured upon the working faces of the jaw. This permits the removal of one or the other of the said biting sections.

In the modified form of the device illustrated in Fig. 7, a portion of a wrench has been shown provided with a stationary jaw 10^c having a central opening 12 with a control nut 15 rotatively mounted therein and engaging upon the lead thread 14 of a movable jaw 13. The stationary jaw 10^c is formed with cavities 26 in which plungers 100

27 slidably engage. Collars 28 are fixed upon these plungers and expansion springs 29 act between the collars and the stationary jaw for normally urging one end of the plunger against the control nut 15. In this condition of the device the other ends of the plungers indicated by reference numerals 30 engage in apertures 31 in the sections of the biting piece 18^b for holding these pieces against displacement. The pieces 18^b are connected by a tongue and groove structure preferably of dovetail form upon the stationary jaw and in engaged position of the plungers 27 the biting sections are held against displacement.

In operation of the device, the wrenches are used in customary manners. In the event that the biting pieces become worn or damaged they may be replaced with new ones. In the form of the invention disclosed in Figs. 1 to 6 inclusive the rivets which hold the biting pieces in place may be removed and then the biting pieces replaced. In the form of the device illustrated in Fig. 7 the nut 15 may be rotated until the lead thread 14 is disengaged therefrom. Then the movable jaw may be removed from the stationary jaw and the control nut also removed for permitting the springs 29 to move the plungers 27 inwards. This causes the ends 30 of the plungers to disengage from the biting pieces which may then be slid off the stationary jaw.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A wrench, comprising a stationary jaw connected with a handle and formed with an aperture, a movable jaw moved by manipulation of a control nut rotatively mounted in the said aperture, biting pieces on the jaws, means for holding the biting pieces in place, and means for automatically moving the holding means to an inoperative position upon removal of the control nut.

2. A wrench, comprising a stationary jaw connected with a handle and formed with an aperture, a movable jaw moved by manipulation of a control nut rotatively mounted in the said aperture, biting pieces on the jaws, means for holding the biting pieces in place, and means for automatically moving the holding means to an inoperative position upon removal of the control nut, said holding means including a plunger.

3. A wrench, comprising a stationary jaw connected with a handle and formed with an aperture, a movable jaw moved by manip-

ulation of a control nut rotatively mounted in the said aperture, biting pieces on the jaws, means for holding the biting pieces in place and for automatically moving to an inoperative position upon removal of the control nut, said means including a plunger, urged against the control nut by a spring.

In testimony whereof I have affixed my signature.

FREDERICK SCHWEIGERT.
